UNITED STATES PATENT OFFICE.

HERBERT T. SNYDER, OF BALTIMORE, MARYLAND.

BOTTLE-SEALING MACHINE.

1,050,868.

Specification of Letters Patent. Patented Jan. 21, 1913.

Application filed June 22, 1912. Serial No. 705,179.

To all whom it may concern:

Be it known that I, HERBERT T. SNYDER, a citizen of the United States, residing at Baltimore, in the State of Maryland, have invented certain new and useful Improvements in Bottle-Sealing Machines, of which the following is a full, clear, and exact specification.

This invention relates to bottle capping machines and has special reference to the mechanism for feeding the caps to the sealing head, the object of the invention being to provide an apparatus of simple construction and arrangement by which the caps will be fed automatically and which, upon failure of the sealing head to act upon the cap fed thereto, will automatically suspend the feeding process until normal conditions are again established.

The invention is illustrated in the accompanying drawings and consists in certain novel features which will be hereinafter first fully described and then more particularly pointed out in the claims following the description.

In the drawings wherein similar numerals of reference are used to indicate corresponding parts in each of the several views:—Figure 1 is a front elevation of the upper portion of a bottle capping machine embodying my invention; Fig. 2 is a similar view of the feeding mechanism on a larger scale; Fig. 3 is a side elevation of the upper portion of the bottle capping machine; Fig. 4 is a similar view on a larger scale of the feeding mechanism; and Fig. 5 is a detail sectional view, showing the loop lever which directly actuates the feeding finger, the shaft on which it is mounted, the roller which rides over said lever, and the yoke on the opposite end of said shaft.

The standard 1 is of the usual form and the sliding bar 2 is mounted in the upper end of the same, said bar being formed with a lateral arm or bracket 3 to which is secured the sealing head 4. A hopper 5 is supported from the bracket 3 and a chute 6 leads from said hopper to convey the caps to and into the lower end of the sealing head, said chute being longitudinally slotted in its outer side.

Secured upon the front of the sealing head, above the lower end thereof, are brackets forming bearings 7, 8, a shaft 9 being journaled in the bearing 8 and a lever 10 being pivotally supported in the bearing 7.

The lower portion of this lever 10 is laterally expanded to form a loop 11 which passes around the chute 6, and to the lower extremity of said lever 10 the feeding finger 12 is pivoted, said finger extending toward the sealing head below the chute and being provided with a cross bar or stop pin 13 which bears against the chute to limit the movement of the feeding finger into the chute. A spring 13^a is carried by the lever and bears upon the feeding finger to hold the finger to the chute. One end of the cross bar 13 is adapted to ride over a spring actuated cam 14 which is pivoted to a bracket 15 as at 15' mounted on the side of the chute, the cam being thus located in the path of the cross bar and being yieldingly held to the chute by a spring arranged in any convenient manner. An arm 16 is rigidly secured to one end of the shaft 9 and the free end of this arm 16 carries a roller 17 which is arranged over and adapted to ride upon the upper edge of the lever 10 while rigid with the opposite end of the shaft is a yoke 18 having inwardly extending flanges 19 at its upper and lower edges. Depending from the yoke is a barrel 20 containing a slidable plunger 21 which is normally projected under the influence of a coiled spring 20' within the barrel. A lever 22 is loosely hung on the shaft 9 immediately adjacent the yoke 18 and passes between the flanges 19, the outer end of this lever being pivoted to the upper end of a link 23 which has its lower end pivoted, as at 24, to a bracket 25 secured on the standard 1.

A spring 26 secured to the chute and the lever 10 tends to draw the lever upward and a stop plate 27 is provided on the chute to arrest said upward movement.

The caps are fed into the chute with the open side outward or downward. The chute being full of caps, when the machine is operated the sealing head descends and crimps a cap onto the bottle. When the sealing head descends, the arm 16 is raised so that the roller 17 is clear of the lever 10 which is then drawn up against the stop 27, by the spring 26, the feeding finger 12, of course, being carried upward with the lever. On this upward movement, the cross bar 13 will ride over the outer surface of the cam 14 and the free end of the finger will, consequently, be withdrawn from its engagement with a cap and will be out of engagement.

until the lever reaches its uppermost position when, having cleared the cam it will spring into engagement with the cap next succeeding the cap previously engaged. Thus, when the head is in its lowest position, having sealed a bottle, all pressure on the caps, in the chute is relieved so that the bottle will not stick in the sealing head and will absolutely clear, and the parts are so adjusted that the push lever does not begin to descend until the sealing head has nearly completed its return stroke and the sealed bottle is then entirely clear of the sealing head.

18 The lever 22 rests upon the plunger 21 which works against the spring in the barrel 20 and the outer end of the lever 22 being pivoted to the upper end of the link 23, the upward movement of the sealing head causes 20 an upward and inward movement of the lever 22 which is transmitted through the plunger and the barrel to the yoke 18. The yoke 18 being fast to the shaft 9, said shaft will be rocked to bring the roller 17 against 25 the lever 10 and cause said lever to travel downward against the tension of the spring 26 so that the feeding finger will move toward the sealing head. The cap engaged by the feeding finger will be pushed toward 30 the end of the chute and a new cap will be pushed into the sealing head. The cross bar on the feeding finger bears against the chute so that the finger can engage the cap only the proper distance and on the down stroke 35 the cross bar passes under the cam so that the finger remains in engagement with the cap during the entire stroke.

Should the operator, for any reason not place a bottle on the table of the machine, 40 on the down stroke of the sealing head, or remove the bottle before it is sealed, the push lever will move to its upper position as previously explained and the feeding finger will engage the cap behind the one previously engaged. With a cap now in the sealing head and the chute full it will be impossible to push another cap into place, and, heretofore, such condition would cause damage to the cap or the feeding mechanism, unless provision is made therefor. With my apparatus, however, when the sealing head rises, the lever 22 resting on the plunger 21 merely compresses the spring in the barrel 20, the lever rotating about the 50 shaft 9 within the yoke 18 so that when the chute is full of caps or is choked up by a broken bottle neck or some foreign substance which will not allow the cap to be pushed into position, the motion of the lever 55 is taken up by the spring, but under normal conditions the motion of the lever is transmitted to the yoke and the caps fed as before described. Should a cap enter the chute in an inverted position, the feeding finger will be unable to enter said cap which

will, consequently, be merely held in the chute and cannot pass down the chute and enter the sealing head.

Having thus fully described my invention what I claim as new and desire to secure by 70 Letters Patent is:—

1. In a bottle capping machine, the combination with a sealing head and a chute leading thereto, of means for engaging and feeding caps successively through the chute to the sealing head, said means comprising a feeding finger, a push lever to which said finger is pivoted, and mechanism including a lost motion device to oscillate said lever. 75

2. In a bottle capping machine, the combination with a vertically reciprocating sealing head, and a chute leading thereto, of a lever pivoted at one end on said head, a feeding finger pivoted to said lever near its opposite end, with mechanism to cause it to 80 engage a cap ready to be sealed and retain its engagement therewith during the entire stroke of the sealing head, said mechanism comprising a cross bar at the end of the feeding finger, means to cause it to bear 85 against the outer side of the chute, a yieldingly mounted cam and means to cause said cross bar to ride over the cam on the up-stroke of the sealing head and to pass under the cam on the reverse or down stroke 90 thereof. 95

3. In a bottle capping machine, the combination with a sealing head, and a chute leading thereto, a lever pivotally supported at one end on said head, a feeding finger pivoted to said lever near its opposite end, resilient means carried by said lever, operating to hold the finger to the chute to engage a cap therein, and mechanism operating as well to limit the entrance of the finger into the chute as to guide the actuated movement thereof, said mechanism comprising a cross bar mounted on said finger, and a spring actuated cam, with means to actuate said lever and cause the cross bar to ride over the cam on a movement of said lever in one direction and to pass under the cam on a reverse movement of said lever in the opposite direction. 105 110

4. In a bottle capping machine, the combination of a sealing head, a chute leading thereto, a lever hung on the sealing head, a feeding finger carried by the lever and engaging the chute, a spring acting on the lever to swing the same upward as the head descends, and a lost motion mechanism acting on the lever to lower the same as the head rises. 115 120

5. In a bottle capping machine, the combination of a sealing head, a chute leading thereto, a lever hung on the head, a feeding finger carried by the lever and engaging the chute, means for raising the lever relatively to the sealing head as the head descends, a stop to limit the upward move- 125 130

ment of the lever relatively to the sealing head, and means for lowering the lever relatively to the sealing head as the head rises.

5 6. In a bottle capping machine, the combination of a sealing head, a chute leading thereinto, a lever hung on the head, a feeding finger carried by said lever and engaging the chute, a second lever connected with 10 a fixed support, and lost motion connections between said second lever and the first mentioned lever.

7. In a bottle capping machine, the combination of a sealing head, a chute leading 15 thereinto, a lever hung on the head, a feeding finger carried by said lever means for raising said lever relatively to the sealing head as the head descends, a rocking arm bearing upon said lever, a second lever and 20 a lost motion connection between it and the rocking arm, with means for imparting a downward movement to the second lever relatively to the sealing head as the head rises.

25 8. In a bottle capping machine, the combination of a sealing head, a chute leading thereinto, a lever hung on the head, a feeding finger carried by said lever means for raising said lever relatively to the sealing 30 head as the head descends, a rocking arm bearing upon said lever, a second lever with a lost motion connection between it and the rocking arm, and a link pivoted at its upper end to the outer end of the second lever and 35 at its lower end to a fixed support.

9. In a bottle capping machine, the combination of a sealing head, a chute leading thereinto, a lever hung on the head, a feeding finger carried by said lever means for raising said lever relatively to the sealing 40 head as the head descends, a rocking arm bearing upon said lever, a yoke rigid with said rocking arm, a second lever extending through said yoke, means for imparting a downward movement to the second lever 45 relatively to the sealing head as the head rises, and a yieldable connection between the second lever and the yoke.

10. In a bottle capping machine, the combination of a sealing head, a chute leading 50 thereinto, a lever hung on the head, a feeding finger carried by said lever means for raising said lever relatively to the sealing head as the head descends, a rocking arm bearing upon said lever, a yoke rigid with 55 said rocking arm, a second lever extending through said yoke, means for imparting a downward movement to the second lever relatively to the sealing head as the head rises, a barrel depending from the yoke, and 60 a spring projected plunger in the barrel bearing against said second lever.

In testimony whereof I have signed my name to this specification in the presence of two subscribing witnesses.
